STEAM ELECTRIC RADIATOR

Morris Koral, New York, N. Y.

Application April 11, 1947, Serial No. 740,791

1 Claim. (Cl. 219—38)

1

This invention relates generally to heating apparatus and more particularly to a steam electric radiator.

In locations where heating of the interiors of rooms or similar structures is only intermittently required, the portability of heating equipment is of great value. In accordance with the present invention heat may be supplied comparable in nature to that provided by central steam heating plants with a considerably reduced initial cost. Since in the present device electricity is used as a source of energy, the thermo unit cost of which is greater than that supplied by the combustion of fuels of the usual nature, it is of importance that the device convert the electric energy into usable heat with a maximum efficiency and that such heat conversion be under constant control to provide for comfort and economy.

It is therefore among the principal objects of the present invention, to provide a novel and highly useful steam electric radiator which is highly portable and convenient in use, requiring principally the connection of its electrical energy supply cord to a suitable convenient outlet or source of current.

Another object herein lies in the provision of the device of the character described which requires a minimum of attention when in operation, and also when not operated.

Another object herein lies in the provision of a steam electric radiator which may have a high heat transfer efficiency and yet which may be of such compact size that the same may be easily fitted in with respect to other furnishings in a room (even where ordinary radiators are in place), and may occupy a minimum of floor space when stored during periods of non-use.

Another object herein lies in the provision of a device of the class described in which the parts are compactly arranged, and are properly protected against accidental damage during shipment from factory to user and during use.

These objects and other incidental ends and advantages will more fully appear in the progress of this disclosure and be pointed out in the appended claim.

In the drawings in which similar reference characters designate corresponding parts throughout the several views:

Figure 1 is a view in perspective of a presently preferred embodiment of the invention.

Figure 2 is an end elevational view of the control housing with the cover plate opened and drawn to one side.

Figure 3 is an electrical schematic diagram.

2

Figure 4 is an enlarged fragmentary longitudinal sectional view partly in elevation of the device shown in Figure 1.

Figure 5 is a front elevational view partly in section of a second embodiment of the invention.

Figure 6 is an end elevational view, as seen from the right of Figure 5 with the cover plate open and drawn to one side.

Figure 7 is a fragmentary horizontal sectional view as seen from the plane 7—7 on Figure 5.

In accordance with the invention the steam electric radiator generally indicated by reference character 10 includes the main radiating element 11, the auxiliary radiating element 12, mounting bases 13 and 14, rolling support means 15 and circuit controlling means 16.

The main radiating element 11 may be composed of a plurality of spaced and parallel steam radiator sections 17. These sections are preferably provided with upper and lower intercommunicating passages 18 and 19, and the sections are maintained in operative connection in any well known manner, for example, by the usual tie rods (not shown). Thus the passages 18 and

19 are formed by the aligned orifices in the radiator sections 17. The sections 17 are preferably of the skeleton type so that a maximum of radiation area is provided. The end sections 24 and 25 are provided with pairs of legs 26, and 26a, which are secured to the mounting bases 13 and 14 respectively. The rolling support means 15 may be in the form of swivel casters.

The end section 24 is provided with an inlet 27 for liquid. The inlet 27 includes an elbow 28

35 and a detachably engageable cover block 29. The elbow 28 is so vertically positioned on the end section 24 so that when the liquid used in the radiator is at the desired level, it reaches substantially to the open upper edge of the inlet 27.

40 In this manner the level of the liquid in the radiator 10 may be observed even though the walls of the sections are opaque.

At the uppermost portion of the section 24 there is provided a pressure relief valve 30. This valve 45 may be of a well known type either spring actuated, or with a rubber cover, or with a fusible metal plug. The relief valve 30 is set at a predetermined value which it is desired that the steam pressure within the radiator shall not exceed. Thus in the event of failure of the thermostat, overheating will cause excess steam pressure which will open the relief valve 30 until sufficient water has been evaporated so that the pressure no longer exceeds the desired value.

55 By this construction, even if the radiator is ac-

cidently left on and the thermostat should fail, safety is assured.

The auxiliary radiating element and control housing 12 is secured in contact with the outermost surfaces 31 and 32 of the end section 25. The element 12 is of generally box-like configuration and includes a top wall 34, a bottom wall 35, and side walls 36 and 37. The free edges of the side walls 36 and 37 have inwardly bent flanges 38 and 39. The cover plate 40 is substantially planar with the exception of the heat entrance louvres 41 and 42 and the heat exit louvres 43. The plate 40 is maintained in detachable connection with the flanges 38 and 39 by means of screws 44 which engage correspondingly positioned orifices 45 in the flanges 38 and 39.

The circuit controlling means 16 includes an indicator 50 which may have the form of a pilot light, a main switch 51, a thermostat 52, terminal blocks 53 and 54 and conductors.

The heating element 60 is preferably of a type in which an electrical resistance element 47 is encased within refractory material covered by a metallic casing 61, so that the resistance element is protected from oxidation while it is operating at elevated temperatures.

Surrounding the casing 61 is a water resistant casing adapted to protect the heating element 60 from any undesirable effects produced by the water in the radiator. At the electrical terminal end 63 of the heater element 60 the same is provided with mounting means adapted to engage the inner wall 33 of the housing and also to make a water tight connection with the lower outer portion of the end section 25. The end 63 of the heater element 60 is provided with the terminal block 54 by means of which contact is made to the resistance element therein.

As best seen in Figures 2 and 3 the line is connected by means of the conductors 70 and 71 to the posts 72 and 73 on the terminal block 53. From the post 72 a conductor 74 travels to the switch 51 thence via conductor 75 to the terminal 76 of the thermostat 52. Leaving the terminal 77 of said thermostat, a conductor 78 travels to the indicator 50. From the indicator 50 one conductor 79 goes to the terminal 73, while the other conductor goes to the terminal 81 on the terminal block 53. Leaving the binding post 81 a conductor 82 goes to the terminal block 54 to connect through the post 83 to the resistance element. The resistance element is indicated by reference character 47 and is disposed within the heater element 60 as has been previously described. The opposite end of the resistance element 47 is connected through the post 84 through the conductor 85 to the terminal 73 previously described.

By virtue of the above described circuit when the switch 51 is closed, below a predetermined temperature the thermostat 52 closes the circuit to the indicator 50 and to the heater element 60 and thence to the return to the line. When the thermostat reaches the predetermined temperature, it opens the circuit indicator, in this case the pilot light becomes extinguished and current is prevented from flowing to the heater element. The thermostat may have an element not shown which is sensitized to heat and which is disposed within the steam chamber 9 within the radiator 10 or the thermostat may be actuated by heat which is conducted to it through the wall 33 upon which said thermostat is mounted.

By virtue of the fact that the auxiliary radiat-

ing element or housing 12 is thermally connected to the main radiator 11, heat from the main radiator element is conducted to the auxiliary radiating element. The conduction of this heat may be facilitated by the use of copper or other heat conducting metal gaskets at points of connection where a seal is desired. The heat from the heater element thus travels by direct conduction where there is contact to the main radiator and to the auxiliary radiator and also through the water which is in the chamber within the main radiator element which upon being converted to steam heats the upper portion of the main radiator and thence by conduction, heat is transmitted to the auxiliary radiating element 12.

Relatively colder air may enter the auxiliary radiating element 12 through the louvres 42 and 41 and travel upwardly to emerge at an elevated temperature through the louvres 43. This movement of and the heating of the air is obtained by the convection flue effect of the auxiliary radiating element 12. Furthermore, the movement of the room air taken as it is from a point close to the floor or other surface upon which the rolling support means 15 are resting has a tempering effect upon the thermostat 52 which is located in the convection flue 100. This effect is of value since without it the thermostat would tend to cut off current to the heater element during a greater period while the room or other enclosure within which the device 10 is being used is first warming up. Thus when the device 10 is placed in a cold room and the switch 51 is closed as soon as the radiator itself reaches the predetermined temperature, the thermostat would cut the current off. Owing to the cooling effect of the air current in the flue 100 the radiator may temporarily reach a higher effective temperature while the room is first warming up. After the room has reached the desired temperature, the warm air current through the convection flue has a moderating effect upon the thermostat so that it reflects more closely the room air temperature in controlling the current reaching the heater element.

The auxiliary radiating element 12 also acts as a physical protection for the thermostat and also encloses the electrical wiring so as to protect the same and also protect the user from contact therewith. Not only is this protection afforded to the parts when the device is installed and when in operation, but also the protection is afforded while the device is in shipment from the factory to the user.

Turning now to the second embodiment of the invention illustrated in Figures 5-7 inclusive for the purpose of avoiding any unnecessary repetition, parts corresponding to those of the first embodiment are given the same reference characters with the addition of the numeral "1" as a prefix.

The principal difference existing between the second embodiment and the prior described embodiment lies in the fact that the inner wall 133, the top wall 134, the bottom wall 135 and the side walls 136 and 137 of the auxiliary radiating element 12 are integral with the main radiating element 11. The flanges 138 and 139 are extended to become annular so that a flange portion is disposed at the upper and lower extremities of the opening within which the cover or panel 40 has a recess fit. The louvres 143 and 142 are flush openings in the cover 40 so that the convection flue 100 may have a similar action to that previously described upon the thermostat.

It may thus be seen that I have disclosed a novel and useful electric steam radiator. My improved radiator is compact and efficient and highly portable. Means are provided for relatively quickly heating a cold enclosure within which the radiator may be used and for feeding power to said radiator to accommodate for the room air temperature changes.

By virtue of the fact that the electrical energy is used to convert water to steam a relatively steady heating effect is obtained even though the power consumption is intermittent. The parts requiring protection are substantially enclosed for the protection of these parts and of the user against electrical shock. Further fragile parts are protected so that a minimum of crating is required when my electric steam radiator is shipped from factory to user. Means are provided for the protection of extensive steam pressure and visible means are provided to determine the proper height of liquid in the boiler portions of my device.

I wish it to be understood that I do not desire to be limited to the exact details of construction shown and described, for obvious modifications will occur to a person skilled in the art.

I claim:

A steam electric radiator comprising: a main radiating element in the form of a closed hollow vessel forming a boiler; a heating element positioned within said boiler so as to heat said water by conduction and radiation; an auxiliary heat

radiating element in the form of a substantially hollow housing having a removable cover, said housing being in contact with said main radiating element; a thermostat disposed within said housing and in conductive relation to said boiler, said housing having an exit opening at the upper portion thereof and an entrance opening at the lower portion thereof forming a convection flue for the passage of room air therethrough; said thermostat being disposed in the electrical circuit with said heater element and a source of power, said thermostat being disposed in the path of the air current produced within the convection flue; whereby said thermostat may be acted upon by heat in the boiler and heat in the air passing through the convection flue within the housing.
